GREENHOUSE STRUCTURE

Johannes Negrijn, Cottingham, England, assignor of one-half to Johannes Fredricus Ludovicus Negrijn, Cottingham, England

Application March 7, 1944, Serial No. 525,403
In Great Britain February 4, 1942

2 Claims. (Cl. 108—1)

The present invention consists in a greenhouse structure comprising the combination of a supporting structure formed mainly or wholly of concrete with separate and readily detachable top-lights.

It has previously been proposed to construct greenhouses and other structures of reinforced concrete elements interfitting and joined together to form a framework span, but it is not believed that there has been any previous proposal for utilising such a framework for closure at the top by top-lights separate from each other and separate from the remainder of the structure and readily detachable therefrom.

The invention is mainly concerned with that type of greenhouse which is used to cover large areas for the purpose of intensive cultivation but, at the same time, the invention may have a useful application to smaller scale greenhouses which may be extended in sections so that private gardeners and smallholders may add new sections to an already existing unit.

In order that it may be clearly understood and readily carried into effect, the invention is hereinafter described with reference to the accompanying diagrammatic drawings, of which:

Figure 1 is an end elevation of an outside span of a greenhouse built up in accordance with the present invention;

Figure 2 is a side elevation corresponding to Figure 1, but broken away in the longitudinal sense;

Figure 3 is a front end elevation of an outside right-hand concrete half-arch member according to the present invention; while

Figure 4 is a front end elevation illustrating a left-hand intermediate concrete half-arch member according to the invention for co-operation, either with an arch as shown in Figure 3, or with a similar half-arch of the same type as shown in Figure 5 but oppositely disposed;

Figure 5 is a front end elevation of an intermediate left-hand concrete half-arch member which may be useful in cases where a wide span is required.

Referring now to the drawings, there is seen in Figures 1 and 2 an end arch-member which is built up by the right-hand half-arch 6R and the left-hand half-arch 6L. Each half-arch member is cast out of concrete and is constituted by a roof bearer extending at an angle from the upper end of each upright, but it will be noticed that the upright of the right-hand half-arch is, in this case, not truly vertical but is preferably sloped outwardly downwards. It is preferable

that such slope should be provided in the case of the outside uprights of each outside span. The uprights are secured in position by being embedded in cement, and it is preferable that a cement foundation, as indicated at 7, shall be provided to enclose the area which is to be covered, but it suffices to locate all those uprights within the area defined by the outer foundation wall in blocks of cement embedded in the soil.

5 The uprights are adapted and arranged so that the roof bearers meet at a central point where they are securely joined by the bolted fish-plate 8, or any other suitable form of joint.

Most clearly seen in Figure 3, there is indicated a notch portion 9 at the top of the roof bearer. A co-operating notch 9 is provided at the top of the roof bearer of the half-arch 6L and the two notches co-operate to form a bed for the reception of the longitudinal $\perp$ section 10 cast concrete beam 10. The arrangement is such that when the structure is assembled and secured, the longitudinal beam 10 is securely seated and presents upwardly at its base-portion edge flanges 10A which slope substantially in alignment with the upper surfaces of the roof bearers. Laterally of the roof bearers notches are provided, that in Figure 3 being represented by the reference numeral 11, whereas a similar notch 12 appears in Figure 4. The notches 11, being at the outside of an outside span, receive a support beam 13, whereas the notches 12 define a trough for the reception of a gutter 14 which, preferably, is of cast concrete in the form shown, the base and two sides defining three adjacent sides of a rectangle, whereas the upper side is constituted mainly by a trough of semi-cylindrical formation. The roof of the structure is completely closed in by the detachable wooden frame standard agricultural lights, represented by the reference numeral 15 in Figure 1. It will be seen that the lights 15 are supported at one end on one of the sloping upper surfaces of one of the edge flanges 10A of the longitudinal beam 10 while, at the other end, the light is supported 45 by the support beam 13. The left-hand half of the arch is covered in the same way by a standard agricultural light but, in the case of the left-hand half-arch and for that matter in the case of all intermediate half-arches, the lights 50 rest on the edge flanges 10A of the longitudinal beam 10 and are laterally supported by the gutters 14, which thus serves the dual purpose of a support and a drain. The lights may be secured in any convenient manner, but it has been found generally practical and convenient simply to tie

a wire or cord between two hooks or projections, the wires or cords being drawn tight up underneath the longitudinal beams 10 or the gutters 14, as the case may be. It is important for the proper draining away and adequate exclusion of weather that the lights 15 shall be securely seated upon the beams 10 and the support beams 13 or gutters 14, as the case may be. It is in fact desirable that the lights 15 should overhang the edges of the gutter 14 quite appreciably, as shown in Figure 1, and for secure and weather-tight seating of the lights the upper edges of the gutters 14 are sloped, as indicated at 14A, to form virtually continuations of the upper surfaces of adjacent roof bearers. It is, furthermore, preferred to provide a small gable-section ridge bar 16 on top of the longitudinal beam 10 to overhang the upper ends of the supported top-lights. The ridge bars 10 may be located by bolts provided at suitably spaced intervals.

The end walls of the individual spans are closed off by letting vertical glazing bars into the arch sections and into the base foundation, the glazing bars being indicated at 17. The glazing bars are preferably provided at their ends with tenons, indicated in dotted lines at 17A, for fitting into mortises moulded in the material of the arch and foundation. Glass is secured in the glazing bars by putty in the usual way. For entry through an end wall, a door frame 18 is provided which mounts any convenient form of hinged door. The side walls are similarly closed in by glass located by the glazing bars, again represented by the reference numeral 17, tenon ended for engagement with mortises in the foundation 7 and the longitudinal support beams 13. The glass preferably rests on rebates 6A formed at the inside edges of half-arches against which it is conveniently secured by putty in the usual way. Rebates 18A are provided in the door frames for the same purpose. Generally, it will be preferable to cast the rebates 6A and the mortises 17B in all arch members despite the fact that, strictly speaking, they are actually required only in conjunction with the end arches; they will in no way be detrimental to the structure, and it can generally be regarded that it is much better to have them available rather than to have to cut them specially if they are not already there.

The uprights of the intermediate half-arches are joined together preferably by bolts, seen at 19 in Figure 1.

The half-arch section shown in Figure 5 merely serves to illustrate a modification which may be desirable in cases where a wide span is provided and additional support is required in order that two standard length lights may be accommodated in the width of each half-span. In this case the notch 20 is provided midway along each roof support for the reception of the longitudinal intermediate supporting beam 21, and the roof is enclosed by lights, of which one is seen at 15' extending between the gutter 14 and the support beam 21, whereas the upper light 15'' is supported partly by the longitudinal beam 10 and partly by resting on the upper edge of the light 15'.

It is the essential feature of the invention that the arch supports and preferably the longitudinal members 10, 13, 14 and 21, are formed from concrete, reinforced if necessary by longitudinal rods or other reinforcing members. The glazing bars 17 and the door frame 18 may be similarly formed of concrete, appropriately reinforced if necessary.

The structure as hereinbefore described is constituted by a plurality of spans and, in practice, it is intended that only the outside and end walls of the structure shall be enclosed so that there is free communication between the spans within the boundary covered by the whole structure.

The standard agricultural lights are readily obtainable as units and can easily be propped open or easily removed for ventilation purposes, and 10 the whole roof structure can be quickly covered in any inclement weather or when there is danger of frost destroying a delicate crop.

Although the invention has been described as applied to the gabled-type of greenhouse, it will 15 be realised that by suitable variation of the sections it may be equally applicable to structures of the lean-to or north-light type, while, again, in the case of large spans, instead of providing only one central longitudinal roof bearer at the 20 apex of each span, an additional longitudinally extending bearer or a plurality of such members may be inserted between the said central member and the gutters.

The invention may also be usefully applied to 25 concrete frame structures for forcing frames, in which case the frame structure may comprise arch supports over which the removable lights are secured, while the side walls of the structure may be glazed or filled in with brickwork or reinforced concrete panels. Where reinforced concrete panels are employed, they may be secured by means of tenons engaging mortises in the arch sections or vice-versa.

What I claim is:

- 35 1. A greenhouse structure comprising a longitudinal series of transverse frames, each including two independent half-arch members, each half-arch member being constructed of concrete and comprising an upright portion and an inclined roof-bearing portion extending laterally from one end of the upright, with the ends of the roof-bearing portions arranged in contact and the uprights in spaced relation to form the transverse frame, each upright portion being 40 formed at its upper end with a notch, a support beam secured in all such notches of the series of transverse frames to tie said frames, the upper surface of the support beam having an inclination in the plane of the adjacent roof-bearing portion to form end bearing sealing support for roof panels, means for securing the meeting ends of the roof-bearing portions of each frame together, such meeting ends of the roof-bearing portions of each frame being notched to form a 45 rectangular recess, an inverted T-shaped support bar fitted in such recesses of the series of transverse frames with the cross bar of the inverted T-shaped support providing end support for roof panels, a ridge bar secured to and bridging the uprights of all inverted T-shaped supports of the series of transverse frames and having a width to overlie all roof panels resting on the inverted T-shaped supports, and roof panels applied to the roof-bearing members with end support on 50 the support beams and on the inverted T-shaped support bar throughout the series of transverse frames, and glass supporting frames in each transverse frame.
- 55 2. A construction as defined in claim 1 where- 70 in the glass supporting members are terminally formed with tenons to fit into mortises molded into the material of the frames.
